UNITED STATES PATENT OFFICE.

CLIFFORD S. JOHNSON, OF MOBILE, ALABAMA, ASSIGNOR OF ONE-HALF TO MORELAND
M. MARSH, OF MOBILE, ALABAMA.

ICE BOX OR REFRIGERATOR.

Application filed September 18, 1922. Serial No. 589,021.

To all whom it may concern:

Be it known that I, CLIFFORD S. JOHNSON, a citizen of the United States, residing at Mobile, in the county of Mobile and State 5 of Alabama, have invented certain new and useful Improvements in Ice Boxes or Refrigerators, of which the following is a specification, reference being had therein to the accompanying drawings.

10 This invention relates to an ice box or refrigerator and it has for its object to provide an improved device of this character constructed in such manner that ready access may be had to the several compartments 15 thereof, while at the same time the entry of air to either the ice or storage compartment will be prevented, when the covers of said compartments are closed.

With the foregoing objects in view, I provide 20 an ice box comprising a plurality of compartments one of which serves as an ice compartment and cools the other compartments and all of which compartments are provided with water retaining troughs 25 therearound into which elements carried by the several covers, enter, when the covers are closed, the water then forming a water seal to positively prevent the entry of air to the several compartments as well as to prevent 30 entry of ants or other insects.

It is a further object of the invention to provide a structure of the character indicated provided with means wherein the drip from the ice compartment is utilized to cool 35 a supply of drinking water under pressure.

Further objects and advantages of the invention will be set forth in the detailed description which follows.

In the accompanying drawings:

40 Fig. 1 is a perspective view of an ice box or refrigerator constructed in accordance with the invention;

Fig. 2 is a transverse vertical sectional view therethrough;

45 Fig. 3 is a plan view thereof;

Fig. 4 is a longitudinal vertical sectional view therethrough; and Fig. 5 is a detail view of a float valve hereinafter described.

Like numerals designate corresponding 50 parts throughout the several figures of the drawings.

In the drawings 5 designates a box like structure preferably of wood and preferably panelled, as indicated at 6, to provide 55 suitable ornamentation. Within the wooden

box 5 is an inner box, preferably formed of metal and indicated at 7 and which inner box may be suitably insulated by insulating material 8 placed between it and the wooden outer box 5. The inner box 7 is divided 60 by sheet metal walls 9 and 10 into the three compartments 11, 12 and 13. The compartments 11 and 13 are cold storage compartments and receive the objects which it is desired to maintain in a chilled condition. If desired, ledges 14 and 15 may be provided within the compartments 11 and 13 for the reception of shelves (not shown). These several compartments are provided with hinged doors or lids 16, 17 and 18 and 70 these doors carry depending sheet metal flanges 19, 20 and 21, the lower edges of which enter a body of water 22 in a trough-like structure 23 which extends around each of the compartments adjacent the top thereof. The lower edges of the flanges 19, 20 and 21 extending below the upper edges of said trough so that the water within the trough will constitute a water seal for positively excluding air from the several compartments when the lids are closed and serving in addition to positively prevent the entry of ants or other insects.

The compartment 12 is provided with a false bottom 24, said false bottom being 85 spaced from the main bottom of the inner metallic box 7 by supports 25 so that a space 26 is left beneath the false bottom within which the drip water from a block of ice supported upon the false bottom may 90 collect. A drinking water service supply pipe 27 enters the box at 28 and extends downwardly to a point below the false bottom 24 where it is extended to form a loop or coil 29. It extends upwardly from said 95 coil and leaves the ice box at 30 being provided with a faucet 31 at its extremity. Thus it is apparent that when the faucet is opened a supply of cold water is instantly available for drinking purposes.

If desired, I may extend a supply line from the service supply pipe 28 into the trough 22, as indicated at 32 and turn the upper end of this pipe down in goose neck fashion, as indicated at 33 and provide a 105 float valve 34 at the outlet of said pipe, said float valve being held in place by a cage 35. This structure serves to keep the water level within the trough 22 at a given point and without any attention upon the 110

part of the user of the refrigerator. If the water level, through evaporation or otherwise, falls below the desired point, the float valve will open and permit a small additional quantity of water to enter to bring the water level back to the desired point whereupon the rise of the float will cause the valve 34^a carried by the float to seat within the mouth of the pipe and cut off the further entry of water to the trough. A drain cock 36 is provided for draining the water from the trough when desired and at this time a valve 37 in the pipe 32 may be closed. A drain pipe 38 leads from the space 26 beneath the false bottom 24 and provides means for drawing off the water from said compartment when desired. This pipe may be provided with a cock 39 if desired.

It is to be understood that the invention is not limited to the precise construction set forth but that it includes within its purview whatever changes fairly come within either the terms or the spirit of the appended claims.

Having described my invention what I claim is:

1. In an ice box construction an outer box and an inner box, the latter being divided into three compartments, the central one of which constitutes an ice compartment, the other of said compartments being chilled by the ice in said central compartment, a water receiving trough extending about the upper portions of all of said compartments and a cover for each of said compartments, each of said covers having

a depending flange extending entirely there-around and entering the water in said trough when said covers are in closed position as and for the purposes stated, a service water supply pipe extending through the ice receiving compartment, a branch extending from the service water supply pipe into the said trough and a float valve controlling the flow of water from said branch into said trough for maintaining a uniform water level in the trough.

2. In an ice box construction an outer box and an inner box, the latter being divided into three compartments, the central one of which constitutes an ice compartment, the other of said compartments being chilled by the ice in said central compartment, a water receiving trough extending about the upper portions of all of said compartments and a cover for each of said compartments, each of said covers having a depending flange extending entirely there-around and entering the water in said trough when said covers are in closed position as and for the purposes stated, a false bottom for the ice receiving compartment, a service water supply pipe extending through the ice compartment beneath said false bottom, a branch leading from the service water supply pipe into the trough and a float valve for controlling the flow of water from said branch to the said trough.

In testimony whereof I hereunto affix my signature.

CLIFFORD S. JOHNSON.
